(57) **CLAIM**

The ornamental design for diaper, as shown and described.

DESCRIPTION

FIG. 1 is a front side perspective view of our new design for a diaper;

FIG. 2 is a rear elevation view thereof;

FIG. 3 is a top plan view thereof;

FIG. 4 is a bottom plan view thereof;

FIG. 5 is a right side elevation view thereof, of which a left side elevation view is symmetrical thereof;

FIG. 6 is a cross-section view along line 6—6 of FIG. 1 thereof; and,

FIG. 7 is a cross-section view along line 7—7 of FIG. 1 of our new design for diaper.

The broken lines are for illustration purposes only and form no part of the claimed designs.
